COMPENSATING SUPERHEATER

Charles W. Gordon, Munster, Ind., assignor to
The Superheater Company, New York, N. Y.

Application May 12, 1934, Serial No. 725,265

5 Claims. (Cl. 122—480)

My invention relates to the art of superheating steam.

A method and arrangement for regulating the temperature of steam from a superheater boiler described in my prior application, Ser. No. 580,290, filed December 11, 1931, involves flowing combustion gases through two paths in the boiler having unequal amounts of superheater surface therein and regulating the final temperature of the steam delivered from the boiler by regulating the proportionate amounts of gases going through the two gas paths. Such method and arrangement have been used with considerable success.

It is an object of the present invention to provide an improved arrangement adapted to operate in accordance with the method described in said application.

The novel features of the invention are pointed out with particularity in the appended claims. The invention, however, together with its objects and advantages, will best be understood from the following detailed description of a superheater boiler which is an exemplification of the invention illustrated in the accompanying drawings and selected from a number of possible embodiments thereof. In the drawings,

Fig. 1 is a sectional elevation through a boiler in accordance with the invention.

Fig. 2 is a section on the line 2—2 of Fig. 1.

Fig. 3 is a section on a line 3—3 of Fig. 1.

Fig. 4 is a fragmentary detail of a connection plate shown in Fig. 1, and ends of units cooperating therewith.

Fig. 5 is a fragmentary view taken from the left of Fig. 4.

The superheater boiler 10 illustrated in Fig. 1 is of the double set bent tube type having a combustion chamber, the upper part of which appears at 12 and on one side of the vertical central plane of which is a steam and water drum 14 connected by generating tubes 16 and 18 to a water drum 20. Wall tubes 21 also connect into drum 14 and extend immediately in front of tubes 16. Tubes 16 form a group in front of and spaced from the tubes 18 leaving a space 22 intermediate two groups of tubes for a downpass for the gases, it being apparent from the drawings that tubes 16 and 21 lie in a zone in which the gases pass upwardly from the furnace. Baffle 24 lies between tubes 16 and pass 22, the gases passing into the upper end of such pass around the top of such baffle. At the side opposite the baffle 24 the pass 22 is defined by a baffle 26 which extends downwardly from 14 but has its lower end spaced from the drum 20 so that the gases pass around its lower

edge into the group of tubes 18. Along the rear edge of tubes 18 is a baffle 28 somewhat similar to 26 and extending down from drum 14. Extending up from drum 20 and lying between baffles 26 and 28, is an intermediate baffle 30 extending upward from the drum 20 but spaced at its upper end from drum 14 so that the gases go first up and then down within the tubes 18, and passing around the lower end of the baffle 28, the gases flow upwardly along a group of down-comer tubes 32 which connect drum 20 with rear steam and water drum 34 which receives the feed water. Connecting nipples 36, 36 run from the upper part of drum 14 to drum 34 to conduct steam into the latter drum. The gases which have passed upwardly along tubes 32 pass therefrom and over nipples 36 and then out of the boiler into the duct 38 in which is a regulating damper 40. Steam from the drum 34 passes out through nipples 40, 40 into a header 42 for saturated steam.

On the opposite side of furnace chamber 12 from the boiler parts above described, is a similar generating section having parts, many of which are exactly alike those already described. Such like parts have been given the same reference characters as those in the boiler section first described, except that the parts in the second mentioned section are primed. Except as about to be mentioned, the construction of the sections of the boiler on the opposite sides of the combustion chamber 12 is the same, and the second mentioned section needs no description in detail. It will be seen, however, that the baffle 24' has an extension 25 running inwardly and downwardly parallel to the tubes 16' so as to restrict the width of the down pass 22' as compared to the width of pass 22. The purpose of such restriction will presently appear. For guiding and supporting the baffle extension 25 the boiler section on the left side of chamber 12 has an additional row of tubes 27 intermediate the group 16' or the group 18'.

The superheater associated with the boiler 10 is also divided into two sections. Such superheater sections, however, are not divided equally between the two boiler sections. One section of the superheater has inlet connections 50 running from the saturated header 42 downwardly to a group of serpentine superheater units 52, 52 interspersed between the tubes 16. Units 52 are looped up and down substantially in the space outlined by the tubes 16 and associated groups of tubes 17, which run up in front of them and form the extensions of generating tubes on the walls of the

combustion chamber. The outlet ends 54 of units 52 extend upwardly somewhat in the rear of the inlet ends and curve downward so that their ends contact with the upper face of a connection plate 56.

In the space outlined by the group of tubes 16' and 17' is a group of superheater units 52' substantially like the units 52, their upper ends 54', however, extend upwardly so as to contact with the lower face of the connection plate 56'. Contacting with the upper face are ends of a group of jumper or extension tubes 55 which extend across toward plate 56 so that their other ends contact with the upper face of such plate. It will be understood, of course, that plate 56 has suitable apertures therein so that steam can pass through them from the upper ends 54' of units 52' into the jumper tubes 55, the construction of plate 56' being analogous to that illustrated in Fig. 4 which shows the plate 56.

At the plate 56 units 52 make connections with the inlet ends 50a of a group of units 52a, 52a. Similarly the units 52a make connection at 56 through jumpers 55, with the upper ends 50b of a group of units 52b (Fig. 3) which lie intermediate the units 52a. Units 52a and 52b lie in the downpass 22, such pass having a greater cross section than pass 22' to provide room for the units 52a and 52b without increasing materially the draft loss in the pass 22 as compared with that of 22'. Units 52 and 52b are of the serpentine type and have outlet ends 52c, 52c, which extend up to a header 58 for superheated steam. From header 58, the steam is conducted to the point or points of use.

It will be seen that the total superheating surface of the boiler 10 is divided into two sections which provide paths of steam flow between the headers 42 and 58. One section is composed of the group of radiant units 52 and a group of convection units 52a connected thereto in series while the other section of the superheater is composed of the group of radiant units 52' and the group of convection units 52b. All the strictly convection units 52a and 52b are, however, on one side of the furnace chamber 12 so that much the greater portion of the superheating surface lies in one of the gas paths through the double set boiler 10 namely the one including the pass 22. Therefore, by adjusting the dampers 41 and 41' so as to throw a greater or less proportion of the heating gases through the pass 22, the temperature of the steam at the header 58 can be held constant within very wide load limits. At an assumed high load close to the maximum for a given boiler, the final steam temperature will be attained with an equal flow of heating gases through the two halves of the boiler. At such load point, dampers 41 and 41' will both be wide open in the position illustrated in Fig. 1. The regulatory effect of the units 52a and 52b is relatively greater when the units 52 and 52' in the radiant or semi-radiant position are substantially unaffected by changes in the proportion of gases flowing through pass 22 and 22' respectively. I have, therefore, arranged the baffles 24 and 24' so as to form a relatively narrow throat at the point 60 at the upper end of the combustion chamber 12 and have placed the serpentine portions of units 52 and 52' all below said throat, only the connecting ends or leads of such units namely parts 52, 52', 54, 54' extending above such throat. As is clear from the drawings, manipulation of dampers 41 and 41' can have little or no effect in throwing the gases toward group 52 or 52', but has a large effect in

throwing a greater or less percentage of the gases over the groups 52a and 52b in the full convection position. However, I do not limit myself to using radiant groups of units of the same heating surface because in some boilers all the surface may be placed on the furnace sides of the baffles and in such cases my invention requires that one semi-radiant group shall have materially more surface than the other.

What I claim is:

1. The combination of two substantially similar banks of generating tubes inclined toward each other to form an upwardly tapering gas space therebetween, two gas off-takes, one for each of said banks and opening on the opposite sides thereof from said space, said banks having each a front group of tubes through which the gases flow upwardly, means forming a down-pass behind each of said front groups, a superheater having units arranged in a plurality of spaced groups, one such group of units interspersed between the generating tubes of each of said front groups of tubes and arranged to receive a material amount of radiant heat, a group of superheater units in one of said down passes, means connecting a portion of the units in the downpass in series with one of said radiant groups, means connecting another portion of the units in said downpass with the other of said groups of radiant units, and means for controlling the gas flow thru one of said uptakes independently of that thru the other.

2. The combination with a double-set bent-tube boiler having groups of vertically inclined generating tubes on each side of an upwardly tapering combustion space, baffle means forming a pronounced throat near the upper end of said space, two groups of semi-radiant serpentine superheater units interspersed among generating tubes at opposite sides of said combustion space and having their serpentine portions substantially below said throat, and additional groups of serpentine superheater units in an entirely convection position at one side of said combustion space, one of said groups of units below said throat connected in series with one group in the completely convection position and the other of said semi-radiant groups connected in series with another group in the convection position, the two pairs of groups in series connected to form two steam paths in parallel, and means for varying the proportion of the total gas flow passing over said groups in the completely convection position to maintain the final steam temperature at a desired point.

3. The combination in a double-set bent-tube boiler of an upwardly tapering combustion space, two groups of serpentine superheater units in semi-radiant location on opposite sides of said space, two groups of serpentine superheater units in a completely convection location on one side of said space, and means for connecting one of said semi-radiant groups in series with one of said convection groups, and means for connecting the other semi-radiant group in series with the other convection group, said connecting means including two connecting plates on opposite sides of the central vertical plane through said space, one of said plates receiving the outlet ends of one of said semi-radiant groups, the other of said plates receiving the outlet ends of the other of said semi-radiant groups, and jumper connecting tubes between said plates, both said groups of convection units having contact with said second mentioned connection plate.

4. The combination in a double-set boiler hav-

- ing an upwardly tapering combustion space of a superheater having two sections connected in parallel, one of said sections having a group of semi-radiant units on one side of said space and connected in series with a group of convection units on the other side of said space, and the other of said sections having a group of semi-radiant units on the other side of said space from those of said first section and having also a group 5 of convection units in series with its radiant units but on the same side of said space, whereby the amount of superheater surface on one side of said combustion space is materially greater than that on the other, and means whereby the gases 10 for heating the boiler can be thrown in greater proportion toward said convection heated portions.
5. The combination with a double-set bent-tube boiler having groups of vertically inclined generating tubes one on each side of an upwardly tapering combustion space, baffling parallel in general the planes of contact between said groups in said combustion space but lying outside of said planes of contact to direct the 15 gas flow in an upwardly tapering path, two groups of serpentine superheater units interspersed among generating tubes at opposite sides of said combustion space, one such group on each side of said combustion space and lying between such space and said baffling, and additional groups of superheater units in an entirely convection position on the side of said baffle removed from said combustion space, one of the groups of units on the furnace side of said baffling connected in series with one group in the completely convection position and the other of said groups on the combustion space side of said baffling connected in series with another group in the convection position, the two pairs 20 of groups in series connected to form two steam paths in parallel, and means for varying the proportion of the total gas flow passing over said groups in the completely convection position to maintain the final steam temperature at a desired point throughout a wide range of load.

CHARLES W. GORDON.
